UNITED STATES PATENT OFFICE.

DAVID KING IRWIN, OF SHORT HILLS, NEW JERSEY, ASSIGNOR TO ECONOMY GLASS COMPANY, OF MORGANTOWN, WEST VIRGINIA, A CORPORATION OF WEST VIRGINIA.

DESIGN FOR A GLASS TUMBLER.

Application filed October 1, 1924. Serial No. 10,933. Term of patent 14 years.

To all whom it may concern:

Be it known that I, DAVID KING IRWIN, a citizen of the United States, and residing at Short Hills, in the county of Essex and State of New Jersey, have invented a certain new, original, and ornamental Design for a Glass Tumbler, of which the following is a specification, reference being had to the accompanying drawing, forming a part thereof, which is a perspective view of a glass tumbler embodying this invention.

I claim:—

The ornamental design for a glass tumbler, substantially as shown.

DAVID KING IRWIN.
